VALVE SPANNER

Malcolm C. Faille, 445 Lansdowne St.,
Rosemere, Quebec, Canada

Filed Mar. 25, 1963, Ser. No. 74,105

Term of patent 14 years

(Cl. D54—16)

FIG. 2

FIGURE 1 is a view in front elevation of a valve spanner showing my new design;

FIGURE 2 is a view in top plan;

FIGURE 3 is a view in bottom plan;

FIGURE 4 is a view in end elevation as seen from the left side of FIGURE 1; and

FIGURE 5 is a view in end elevation as seen from the right side of FIGURE 1.

I claim:

The ornamental design for a valve spanner, as shown.
